MINIATURE BULB AND SOCKET
CONSTRUCTION

Maximilian Klein, Sellersville, and William E. Pfeffer, South Perkasie, Pa., assignors to United States Gauge Company, Sellersville, Pa., a corporation of Pennsylvania

Application November 29, 1938, Serial No. 243,048

6 Claims. (Cl. 176—32)

The present invention relates to a novel electric lamp and socket structure especially designed for the illumination of instruments, such as gauges of all kinds, electrical indicating instruments, clocks or the like. More particularly, the present invention relates to a novel miniature lamp and socket structure adapted for use in the illumination of dial and pointer instruments, which permits ready application of the lamp to the socket with the lamp bulb extending away from the part that is gripped by the fingers in inserting the lamp in the instrument.

Electrical bulbs for indicating instruments are extremely small, having an overall length of approximately one-half an inch and a diameter of approximately one-eighth of an inch. As a result of the small size of these bulbs, difficulty has been experienced in assembling the glass bulb with its extremely fine filaments in the bulb base.

It is a primary object of the present invention to provide a simple base structure that will enable ready assembly and connection of the glass bulb and filament to the base.

A further important object of the present invention resides in the provision of an electric lamp or base assembly having one contact in the form of a sleeve at the front end of the assembly, and the other contact likewise of sleeve-like form but disposed at the rear end of the assembly, so as to provide the peripheral margin of the base.

A further object of the present invention resides in the provision of an electrical lamp base made up of three relatively simple sleeve-like elements designed to be held in assembled relation with each other and with a suitable cement serving to encase the bulb at one end and thus provide the lamp base.

Still another object of the present invention resides in the provision of a novel combination of holding cap and lamp designed to permit easy replacement of the lamp in the cap.

A further object of the present invention resides in the novel association of a socket, provided by a bore in the casing of an indicating or light instrument, and a miniature lamp and lamp holder permitting illumination of the instrument interior upon assembly of the lamp and holder in said bore.

Further objects of the invention will appear from the following description when read in conjunction with the appended claims and attached drawing wherein:

Figure 1 is an enlarged transverse sectional

view through a bulb socket made in accordance with the present invention and illustrating the novel bulb in operative relation thereto.

Figure 2 is an enlarged transverse sectional view of the novel bulb assembly of the present invention illustrating the manner of insulating the contact elements from each other and of securing the glass bulb assembly in place.

Figure 3 is a view of the bulb of Figure 2 as seen from the front of the bulb.

Figure 4 is a view of the bulb of Figure 2 as seen from the rear of the bulb.

Figure 5 is a view similar to Figure 2 illustrating a modified form of bulb assembly.

With continued reference to the drawing 15 wherein like reference numerals are used to indicate the same parts throughout the several figures, numeral 10 indicates generally a lamp made in accordance with the present invention, and numeral 11 indicates generally the novel 20 socket of the present invention.

Lamp 10 comprises a glass bulb 12 having the usual filament 13 therein and protruding filament connections 14 and 15 extending from the rear of the glass bulb. Glass bulb 12 is preferably manufactured in accordance with well known practices and is associated with the novel bulb base assembly 16 of the present invention in the following manner:

Base assembly 16 comprises a metal sleeve 17 having an annular flange 18 at one end thereof. Sleeve 17 comprises one contact element for bulb 10 and is connected to filament lead 14 by a suitable soldering operation at 19.

After sleeve 17 is connected to filament lead 35 14, insulating sleeve 21 is telescoped thereon until the shoulder 18 abuts against the end 22 of sleeve 21.

The assembled glass bulb 12, sleeve 17 and sleeve 21 is then provided with a further sleeve 40 23 having an annular flange 24 at one end thereof. Sleeve 23 is also provided with a shoulder 24a designed to abut end 25 of sleeve 21. A split ring 24b is loosely disposed on the portion of sleeve 23 between flange 24 and shoulder 24a. 45 Ring 24b in its expanded position extends beyond the periphery of sleeve 21 and flange 24 for a purpose to be presently pointed out. Sleeve 23 with ring 24b in place is forced into the opposite end of sleeve 21 until shoulder 24a 50 abuts end 25 of sleeve 21. Filament lead 15 is then soldered to sleeve 23 at 26. Bulb assembly 10 is then filled with a suitable cement 27 by pouring the cement in its plastic condition into the open rear end of bulb assembly 10. Cement 55

27 completely fills the space between glass bulb 12 and sleeves 17, 21 and 23 so as to firmly connect these elements together.

From the above description it will be clear that 5 bulb 10 is made of relatively few and simple parts, and that, due to the fact that the various parts are readily accessible during the assembly operation, very little difficulty is experienced in making the soldered connections 19 10 and 26, and in assembling the glass bulb 12 with its base 16.

While bulb 10 may be used in any suitable socket structure, the socket structure 11 of the present invention is at present preferred. Socket 15 11 is specifically described and claimed in applicants' co-pending application Serial No. 243,047, filed on even date herewith and entitled "Minature bulb and socket construction." Socket 11 comprises a body portion 31 of insulating material 20 having a bore 32 therein. Body portion 31 may be formed as an integral part of the casing of an indicating instrument, which is to be illuminated by the lamp of the present invention. The upper end of bore 32 is preferably 25 recessed, as at 33 to provide an annular shoulder 34. At suitable points in the interior of body 31 the walls of bore 32 are provided with longitudinally extending grooves 35 and 36. Grooves 35 and 36 receive electrical conductors 37 and 30 38 which are connected in any suitable manner to a source of electrical energy.

Conductor 37 preferably constitutes the live conductor and is provided with an annular contact portion 39 having a centrally disposed opening 41 therein. In order to properly position contact 39 in bore 32, conductor 37 is secured to an insulating sleeve 42 as by means of suitable arms 43 carried by the conductor which pass through suitable apertures 44 in the wall of sleeve 42. Arms 43 are bent over so as to clamp portion 45 of sleeve 42 at 46. Sleeve 42 with conductor 37 secured thereto is then inserted into bore 32, preferably from the lower end, and forced upwardly through bore 32 until contact 39 is at the proper level. While a frictional fit between sleeve 42 and bore 32 is usually sufficient to retain the sleeve in proper position, suitable cement may be used.

Conductor 38 in groove 36 extends beyond the 50 shoulder 34 and is then bent over to provide a portion 48 in engagement with shoulder 34 and a portion 49 in engagement with the wall of recess 33 of bore 32. A metal ring 51 having internal threads 52 therein is positioned in recess 33 and 55 clamps portions 48 and 49 of conduit 38 in place.

Metal ring 51 may be associated with body 31 in any suitable manner. Preferably, however, the ring 51 fits recess 33 snugly so as to be retained by friction. The body 31 is made of insulating material such as "Bakelite", it is to be understood that ring 51 may be cemented to said body if desired.

Ring 51 in the illustrated embodiment is adapted to receive an externally threaded lamp-receiving metal cap 53 having an internal bore 54 therein. Bore 54 receives base 16 of lamp 10. As base 16 is inserted into bore 54, ring 24b is contracted and, due to its tendency to expand frictionally, secures lamp 10 in cap 53 so as to permit handling 65 of the assembly as a unit. In its final position in cap 53 lamp 10 engages the tapered walls 55 of cap 53 along the corners of contact 24. Engagement of walls 54 and contact 24 insures an adequate electrical contact between the cap and the 70 lamp. Cap 53 completes the return circuit from 75

filament 13, contact 24 to metal ring 51, and conduit 38. When the cap 53 is firmly screwed in the ring 51, the flange 18 of contact sleeve 17 bears against contact ring 39, current flowing to the filament from conductor 37, through ring 39, 5 sleeve 17 to the filament 13. It will be understood that a suitable opening is provided in the wall of the socket so that the rays of light emanating from the lamp may pass in the direction needed to properly illuminate the dial and/or 10 pointer of the instrument, all as more completely described in the application of Maximilian Klein and William E. Pfeffer, entitled "Illuminating indicating instruments," filed on even date here- 15 with.

While the socket 11 of the present invention has been described as being formed from a body 20 31 of insulating material, it will be appreciated that body 31 may be formed of metal by use of a suitable insulated conduit 37. If such a structure is resorted to, ring 51 and conduit 38 may be omitted and the cap 53 may be screwed directly into the metal body portion. In such a construction, the metal body of the socket which is connected in suitable manner to the ground lead of 25 the electrical source, will serve as the return line from bulb 10.

Figure 5 discloses a modified form of lamp assembly substantially like that shown in Figures 1 to 4. This form of the invention differs from that 30 previously described in that sleeve 23 is omitted and a second sleeve 17' is substituted therefor. In all other respects, this form of the invention is like that previously described. As a consequence, the same reference numerals have been 35 employed and a detailed description is believed to be unnecessary.

The invention may be embodied in other specific forms without departing from the spirit or 40 essential characteristics thereof. The present embodiments are therefore, to be considered in all respects as illustrative and not restrictive, the scope of the invention being indicated by the appended claims rather than by the foregoing description, and all changes which come within the 45 meaning and range of equivalency of the claims are therefore intended to be embraced therein.

What is claimed and desired to be secured by United States Letters Patent is:

1. A lamp, comprising a closed bulb having a 50 filament therein, and a base consisting of two conductor sleeves disposed in spaced relation end- 55 wise of said bulb, said sleeves being of equal diameter, an insulating sleeve electrically separating said conductor sleeves and forming with said conductor sleeves a base having smooth external surface, connections between said filament and said conductor sleeves, and cementitious material in certain of said sleeves providing a closure completely housing one end of said bulb.

2. The lamp defined in claim 1 in which said conductor sleeves comprise annular body portions terminating at one end in an external annular flange, said sleeves being arranged in reversed relation on said bulb, and in which said insulating sleeve is disposed in the angles formed by said annular shoulders and forms a flush joint with the conductor sleeves.

3. An electric lamp having a base consisting of two conductor sleeves providing annular electrical 70 contacts of equal diameter, an insulating sleeve separating and spacing said conductor sleeves axially thereof, and cementitious insulating material cooperating with said sleeves to complete said base, said conductor sleeves and said insu- 75

lating sleeve being formed to provide said base with a smooth and uninterrupted external surface.

4. An electric lamp having a base including two identical axially separated contacts each of which is in the form of a sleeve having one end terminating in an external annular flange, and an insulating sleeve separating said contacts, said base being adapted for assembly with a standard bulb structure by telescoping either end of said sleeve over the predetermined end of said bulb structure.

5. An electric lamp, comprising a bulb having a filament therein and a base consisting of two conductor sleeves disposed in spaced relation end-wise of said bulb, an insulating sleeve electrically separating said conductor sleeves, said conductor sleeves and insulating sleeve together forming a smooth external annular wall, a split snap ring

interposed between a portion of one of said conductor sleeves and said insulating sleeve, connections between said filament and said conductor sleeves, and cementitious material in certain of said sleeves providing a closure completely housing one end of said bulb.

6. A lamp and cap assembly, consisting in a cap having a smooth cylindrical bore for the removable reception of the base of said lamp, a normally expanded snap ring mounted in the external wall of said base for frictionally engaging the wall of said bore to removably secure the lamp in said cap, a threaded connection on said cap for connection to a socket and a portion on said cap providing a finger grip to permit the cap with the bulb therein to be threaded into said socket.

MAXIMILIAN KLEIN.
